By Attorney.

UNITED STATES PATENT OFFICE.

SØREN CHRIS REPHOLDT, OF OMAHA, NEBRASKA.

MOP-WRINGER.

1,268,055.

Specification of Letters Patent. Patented May 28, 1918.

Application filed September 13, 1917. Serial No. 191,169.

To all whom it may concern:

Be it known that I, SØREN CHRIS REPHOLDT, a citizen of the United States of America, residing at Omaha, in the county 5 of Douglas and State of Nebraska, have invented certain new and useful Improvements in Mop-Wringers, of which the following is a specification.

This invention relates to certain new and 10 useful improvements in mop wringers.

The primary object of the invention is the provision of a device adapted for extracting water from a mop without the necessity of employing the hands of the operator, the 15 device being adjustable for employment with buckets of different sizes.

A further object of the device is the provision of a mop wringer adapted for squeezing a mop by mechanism operated 20 either by hand or foot power, receiving means being arranged for the expelled fluid, and the wringer mechanism being adjustably and removably carried by a support provided for the device.

25 A still further object of the invention is the provision of a device possessing great strength and adapted for easily extracting fluid from articles such as fabrics placed therein, the device being readily moved about and also serving as a bucket holder 30 during the mopping as well as the wringing operation.

In the drawing forming a part of this application and in which like designating 35 characters refer to corresponding parts throughout the several views,

Figure 1 is a view of the device partly in side elevation and partly in vertical section, the inoperative position of the wringer 40 mechanism being indicated by dotted lines as well as the operative position of different sized buckets employed therewith.

Fig. 2 is a rear elevation thereof.

Fig. 3 is an enlarged perspective view of 45 the rear portion of the device illustrating the adjustable holding means for the wringer mechanism.

Fig. 4 is an enlarged perspective view 50 of the lower rear portion of the wringer mechanism showing a portion of the pedal device, and

55 Figs. 5 and 6 are enlarged side views of the adjustable connections between the supporting standard of the base and the legs of the wringer mechanism illustrating the adjustability of the members.

Referring more in detail to the drawing, the device broadly consists of a base or supporting member 10 having a wringer mechanism 11 adjustably and removably carried thereby and serving for removing fluid from a mop positioned within the box or receiver 12 of the mechanism and located above a bucket 13 of any suitable size which is employed in mopping, and which is mounted 65 upon a platform 14 forming a part of the base 10.

The platform 14 is preferably provided with a marginal flange 15, the base 10 being supported on casters 16 upon which the device is readily moved whenever desired during the mopping operation. A pair of standards 17 are carried by the base 10 at the rear of the platform 14, being substantially T-shaped in cross section, and have the webs 70 21 thereof provided with V-shaped slots 18 and bayonet shaped slots 19, the slots 18 and 19 in each web 21 alternating, and the slots in one web 21 being in horizontal alignment with the slots in the other web. 80

The box 12 carries legs 20 depending from the rear portion thereof and arranged in parallelism, preferably formed of sheet metal and adapted for reception between the webs 21 of the standards 17. Transversely 85 extending rods 22 are carried by the legs 20, adjacent the lower ends thereof and suitably spaced apart for ready reception within the slots 18 and 19, it being noted that sockets 23 and 24 are provided at the bottoms of 90 the slots 18 and 19, respectively, and are adapted for the seating reception of the rods 22 when the box 12 is arranged in its operative position with the legs 20 vertically disposed. 95

A presser board 25 is pivoted as at 26 within the bottom of the box 12 and is connected by a link 27 to an arm 28 secured upon an operating shaft 29 journaled at the rear upper corner of the box and having an 100 upturned end portion 30 serving as a hand lever for operating the presser board. A bail 31 is secured to the shaft 29 and projects rearwardly of the box 12 on which a U-shaped treadle member 32 is pivotally hung 105 and is slidably arranged through a guide 33 carried by the legs 20, the member 32 having a rearwardly extending lower end portion 34 constituting a pedal. Springs 35 encircle the treadle member 32 and bear between the guide 33 and collars 36 secured to the treadle member above the said guide 110

whereby the treadle member is normally maintained elevated, with the presser board 25 in its rearward position, permitting the ready insertion of the mop into the box 12.

The complete operation of the device will be apparent from this detail description thereof, it being noted that the wringer mechanism is normally arranged with the box 12 positioned above the platform 14 and over a bucket as 13 that is mounted on the platform. The device may be readily moved wherever desired while mopping, and the mop positioned within the box 12 when it is found desirable to wring the same, this operation being accomplished by rearwardly moving the hand lever 30 or by depressing the treadle member 32 by placing the foot of the operator upon the pedal portion 34 thereof. The box 12 may be positioned at different elevations by providing a plurality of pairs of slots in the standards 17, a lower set of V-shaped slots 18' and an upper set of inclined slots 19' being herein shown. This vertical adjustment of the box 12 permits the employment of buckets 13 of different sizes, while a cutaway portion or notch 37 is provided in the bottom 38 of the box 12 which permits the box to be positioned slightly within the top of the bucket 13 and accommodating the latter upon the platform 14. When it is desired to remove the bucket 13 or to render the wringer 11 inoperative, the upper bar 22 may be moved outwardly of the sockets 24 and into the inclined slots 19 within which the upper bar is positioned, while the lower bar 22 will be moved rearwardly, engaging the forward ends 39 of the V-shaped slots 18 or 18' and retaining the wringer mechanism in rearwardly inclined position as illustrated by dotted lines in Fig. 1 of the drawing, the positions of the bars 22 within the said slots being indicated in Fig. 6. When it is desired to detach the wringer mechanism from the support 10, the bars 22 are elevated out of the sockets 23 and 24 and moved outwardly through the inclined slots 19 or 19' and the outer portions of the V-shaped slots 18 or 18' thereby disconnecting the legs 20 from the standards 17 as will be evident in Fig. 5 of the drawing. During the wringing operation, the board 25 is moved forwardly against the mop or other articles within the box 12 while the fluid passes through slots 40 and 41 in the front wall and bottom respectively of the box into the bucket 13 arranged therebeneath. Handles 42 are provided upon the opposite sides of the box 12 for convenience in moving the device as well as in detaching the wringer mechanism 11 from the support 10.

What I claim as new is:—

1. A mop wringer comprising a receptacle supporting base, a wringer mechanism tiltably and adjustably mounted thereon where-

by the same may be bodily tilted and adjusted vertically relative to said base, and operating means for the wringer mechanism.

2. In combination, a receptacle supporting base, upright standards upon the base, a box connected to said standards, a presser board within the box, an operating shaft carried by the box, operative connections between the shaft and presser board, a guide secured between said standards, and treadle means operatively connected to said shaft and slidably arranged through said guide.

3. In combination, a receptacle supporting base, a wringer mechanism including a box tiltably mounted on said base, said box being provided with fluid outlet openings in the walls thereof and with a cut-away portion adjacent its rear side adapted for accommodation of the upper portion of the receptacle upon the supporting base, and means for operating said wringer mechanism.

4. A device of the class described comprising a base, a wringer mechanism including a box, upright standards upon the base having horizontally aligned V-shaped and inclined slots therein, depending parallel legs carried by the box and arranged between said standards, and parallel rods carried by said legs removably received within said slots, said rods being positionable in said slots to retain the wringer mechanism at an inclination with respect to said standards.

5. In combination with a wringer mechanism and a support therefor, parallel upright standards carried by the support and having a V-shaped slot and an inclined slot rearwardly opening at the free edges of the standards and with sockets at the bottoms of said slots, depending legs carried by the wringer mechanism, parallel rods carried by said legs adapted for reception within said slots and for seating in said sockets when the legs are arranged parallel with said standards and the device is operatively positioned, one of said rods being arranged at an intermediate point within the inclined slots and the other rod being arranged at the rear ends of said V-shaped slots when the legs are in their adjusted angular arrangement with respect to said standards.

6. In combination, a receptacle supporting base, upright standards upon the base, a wringer mechanism provided with depending legs tiltably and adjustably connected to said standards whereby said mechanism may be bodily tilted and adjusted vertically relative to said base, and operating means for the wringer mechanism.

7. In combination, a receptacle supporting base, a wringer mechanism including a box, tiltably and adjustably mounted on said base, said box being provided with fluid outlet openings in the walls thereof, and

with a cut-away portion adjacent its rear side adapted for accommodation of the upper portion of the receptacle upon the supporting base, and means for operating 5 said wringer mechanism.

8. In combination, a receptacle supporting base, upright standards upon the base, a wringer mechanism including a box connected to said standards, a presser board 10 within the box, an operating shaft carried by the box, a guide secured between said standards, a treadle means operatively connected to said shaft and slidably arranged

through said guide, and means associated with the treadle means to maintain the 15 board in its rearward inoperative position.

9. In combination, a supporting base upon which a receptacle may be placed, an upright standard rigid with and extending upwardly from the base, a vertically adjustable wringer mechanism provided with a depending leg tiltably and detachably connected to said standard, and operating means for the wringer mechanism.

In testimony whereof I affix my signature. 25
SØREN CHRIS REPSHOLDT.
